(57) **CLAIM**

The ornamental design for a display panel portion with an animated icon, substantially as shown and described.

DESCRIPTION

FIG. 1 is a first image in a sequence for a display panel portion with an animated icon, showing my new design.

FIG. 2 is a second image in the sequence thereof.

FIG. 3 is a third image in the sequence thereof.

FIG. 4 is a fourth image in the sequence thereof.

FIG. 5 is a fifth image in the sequence thereof.

FIG. 6 is a sixth image in the sequence thereof.

FIG. 7 is a seventh image in the sequence thereof.

FIG. 8 is an eighth image in the sequence thereof.

FIG. 9 is a ninth image in the sequence thereof.

FIG. 10 is a tenth image in the sequence thereof.

FIG. 11 is an eleventh image in the sequence thereof.

FIG. 12 is a twelfth image in the sequence thereof.

FIG. 13 is a thirteenth image in the sequence thereof.

FIG. 14 is a fourteenth image in the sequence thereof.

FIG. 15 is a fifteenth image in the sequence thereof.

FIG. 16 is a sixteenth image in the sequence thereof.

FIG. 17 is a seventeenth image in the sequence thereof; and,

FIG. 18 is an eighteenth image in the sequence thereof.

The appearance of the animated icon sequentially transitions

between the images shown in FIGS. 1-18.

The process or the period, in which one image transitions to

another image forms no part of the claimed design.

The broken lines showing a display panel portion and portions of the animated icon in FIGS. 1-18 form no part of the claimed design.
